UNITED STATES PATENT OFFICE.

CHARLES A. HULTQUIST, OF LOS ANGELES, CALIFORNIA.

PNEUMATIC DRILL.

Application filed October 29, 1923. Serial No. 671,352.

To all whom it may concern:

Be it known that I, CHARLES A. HULTQUIST, a citizen of the United States, residing at Los Angeles, county of Los Angeles 5 and State of California, have invented a new and useful Pneumatic Drill, of which the following is a specification.

This invention relates to rock drills of the elastic fluid operated type, and more 10 especially to the type employing a water tube.

When pneumatic drills employing water tubes are used, said tubes are subject to breakage or clogging and, in either event, 15 the water tube must be removed and repaired or another one substituted for it. With prior drills of this type, it is necessary, in order to remove the water tube, to take the machine apart, and this entails the 20 unbolting of at least three different parts of the drill and exposing the ends of said parts to the dust that is always present during mining operations. The three parts mentioned are the hammer and feed cylinders 25 and the valve block that is interposed between them. When these parts are again assembled, any dust remaining on their end faces prevents the making of leak-proof joints and such dust and even small particles of rock are very apt to fall into the 30 air feed control port and lodge between the wall of the feed cylinder and the cup leather, doing injury to both.

Because of liability to injury by dust, if 35 the repair be made in the mine, it has heretofore been customary and practically necessary to hoist the drilling machine to the surface of the earth and have the necessary repair to the water tube made in a shop. 40 This hoisting of the machine to the surface consumes valuable time and also delays the hoisting machinery in the performance of other necessary operations, thus increasing the mining costs.

45 To overcome the foregoing objections I have previously invented a construction in which the feed cylinder and valve block are connected by a hinge, and a latch releasably holds the valve block closed upon the feed 50 cylinder. With such construction, first disclosed in my copending application for patent, filed August 14, 1922, Serial No. 581,633, the air feed control port passes through the hinge pintle, and an object of their invention, is to simplify the construction so that 55 the air feed port is protected from dust

without the necessity of extending said port through the hinge pintle.

The accompanying drawings illustrate the invention:

Figure 1 is a longitudinal view of a pneumatic drill constructed in accordance with the provisions of this invention, a portion of the drill steel being broken away to contract the view.

Fig. 2 is a plan view of the valve block, the hammer cylinder being omitted.

Fig. 3 is an enlarged fragmental section on the line indicated by 3-3, Figure 1.

Fig. 4 is a longitudinal view of the valve.

Referring to the drawings, the valve block is indicated at 8 and is secured by bolts 9, or other suitable means, to the hammer cylinder 10. In the cylinder 10 is the usual hammer 50. Extending transversely of the valve block 8 is a cylindrical chamber 11 in which is positioned a rotary valve 12. The valve chamber 11 communicates through a port 13 with the bore 14 of the cylinder 10. Thus when the valve 12 is appropriately turned it permits the operating fluid to flow from the feed pipe 15 through the axial valve bore 28 and port 16 of the valve and through the port 13 to the cylinder bore.

The valve block 8 seats against the upper end of a feed cylinder 17 which contains the usual plunger 18 acted upon by compressed fluid to feed the cylinder 10 so that the drill steel will be continually forced against the rock being operated upon. In order to supply the feed cylinder 17 with compressed fluid, it has heretofore been customary to pass the fluid from the valve chamber to the feed cylinder, the port or duct for carrying the fluid passing from the valve block into the upper end of the feed cylinder across the joint 19 between the valve block and the feed cylinder, and thus, when the valve block and feed cylinder were separated, particles of rock were quite apt to lodge in the duct. I avoid this difficulty, even though the former duct construction is retained, as will be made clear hereinafter.

A duct 20 in the wall of the feed cylinder 105 communicates with the bore 14 of the feed cylinder and opens to the joint 19 so that, when the valve block is closed upon the cylinder, the duct 20 will communicate with a duct 25 in the valve block. When the valve 110 12 is in the position shown in Figure 3, the duct 25 communicates with a duct 26 ex-

tending longitudinally of the valve, and said duct 26 at the same time registers with a port 27 opening through the wall of the valve chamber to the atmosphere. This, as will be clearly understood, permits discharge of operating fluid from the feed cylinder 17.

The bore 28 of the valve is provided with a port 29 communicating with a duct 30 elongated circumferentially of the valve 12. When the valve is turned to register the port 16 with the port 13, the duct 30 registers with the duct 25 so that, not only is the operating fluid admitted to the cylinder 10, but also to the feed cylinder 17.

A water tube is shown at 31 and is packed in the usual manner by packing 32 contained in a recess 33 in the valve block 8. The packing 32 surrounds the tube 31 between one end of the recess 33 and a flange 34 on the water tube. Bearing against the flange 34 is a plug 35 which is screw-threaded into the valve block, thus detachably holding the water tube in place. The water tube 31, as is customary, extends through the hammer, as indicated in dotted lines in Fig. 1. The water tube is supplied with water from a supply pipe 310 through a duct 311 in the valve block and furnishes water to the drill steel 44, in a manner well understood in this art.

The valve block 8 is provided with an ear 41 through which extends a bolt 42 constituting a pintle or pivot whose axis is parallel with the longitudinal axis of the feed cylinder 17. The pintle 42 also extends through an ear 43 of the feed cylinder 17, thus hingedly connecting the valve block and cylinder 17.

Preferably the outer ends of the ducts 20, 25 are positioned so that the ear 41 will close over the duct 20 and the ear 43 over the duct 25, when the valve block is swung into open position, thus making it as impossible for dust to have access to said ducts as when the valve block is in closed position. Thus the valve dust cannot be entrained by the operating fluid and lodge in the bore of the feed cylinder between the plunger and the wall 50 of the cylinder.

On the side of the valve block opposite to that having the valve is a longitudinal slot 36 in which is pivoted a latch bolt 37, the pivot being indicated at 38. The bolt is

adapted to extend through a slot 39 in the feed cylinder 17, and the nut 40 of said bolt is adapted to bear against the feed cylinder to releasably hold the valve block closed upon the feed cylinder. To gain access to the water tube 31, the latch bolt 37 will be released and the valve block will then be swung laterally on its pintle 42. The operator will then unscrew the plug 35 and remove the water tube 31.

I claim:

1. In a pneumatic drill, the combination of a feed cylinder having an ear, a valve block having an ear, a pintle connecting the ears, a water tube detachably engaging the valve block, and a valve mounted in the valve block, there being an air duct in the valve block controlled by the valve and opening to the joint between the valve block and feed cylinder and there being an air duct in the feed cylinder communicating with the bore of the cylinder and with the first duct when the valve block is in closed position, the outer ends of the ducts being positioned to be closed by the ears when the valve block is swung into open position.

2. In a pneumatic drill, the combination of a valve block having a water supply duct, a cylinder connected with the valve block, a hammer in the cylinder, a water tube receiving water from said duct and extending through the hammer and detachably engaging the valve block to supply water to the drill, a feed cylinder hingedly connected to the valve block, the feed cylinder having a duct communicating with the feed cylinder bore, the valve block having a valve chamber and having a duct connecting said chamber with the duct in the feed cylinder when the valve block is closed on the feed cylinder, the hinge connection closing the outer ends of the last two ducts when the valve block is in open position, there being a port in the valve block connecting the valve block with the bore of the hammer containing cylinder, a plunger in the feed cylinder, a valve in the valve chamber controlling the port and duct in the valve block, and means to releasably hold the valve block closed upon the feed cylinder.

Signed at Los Angeles, Calif., this 22d day of October, 1923.

CHARLES A. HULTQUIST.
